UNITED STATES PATENT OFFICE.

WILLIAM JASPER SNOW, OF VILONIA, ARKANSAS, ASSIGNOR OF ONE HALF
TO JOHN H. DAVIS, OF VILONIA, ARKANSAS.

MILK-CAN.

SPECIFICATION forming part of Letters Patent No. 748,805, dated January 5, 1904.

Application filed April 13, 1903. Serial No. 152,427. (No model.)

To all whom it may concern:

Be it known that I, WILLIAM JASPER SNOW, a citizen of the United States, residing at Vilonia, in the county of Faulkner and State of 5 Arkansas, have invented certain new and useful Improvements in Milk-Cans; and I do declare the following to be a full, clear, and exact description of the invention, such as will enable others skilled in the art to which it applies 10 pertains to make and use the same.

My invention relates to certain new and useful improvements in milk-cans.

The object of the invention is to provide a can or receptacle with a self-closing cover or closure which will prevent the loss of the contents should the can be overturned and which will prevent all dirt and foreign matter from entering the can or vessel.

A further object is to provide a device of 20 this character which is simple in construction, durable in use, efficient in operation, and comparatively inexpensive of production.

With these and other objects in view the invention consists of certain novel features of 25 construction, combination, and arrangement of parts, as will be more fully described, and particularly pointed out in the appended claim.

In the drawings, Figure 1 is a side elevation 30 of my improved milking-can. Fig. 2 is a vertical sectional view through the upper portion of the same. Fig. 3 is a detail horizontal section through the valve.

Referring more particularly to the drawings, the numeral 1 denotes the can or receptacle, which is provided with the handles 2 and the open screw-threaded upper end 3.

4 denotes a cap or cover, the upper conical portion or inlet-funnel 5 of which is connected 40 by the neck 6 to the lower conical portion 7, the lower end of which is threaded to engage with and close the open upper threaded end 3 of the can.

In the neck 6 I provide a slide-valve 8, consisting of the two parallel spaced horizontal plates or disks 9, provided with the registering ports or openings 10 and the slide or valve 11, which operates between said disks and

which is adapted to be guided by same to close said ports and cut off communication 50 between the inlet-funnel 5 and the interior of the can. Said slide-valve 11 has one end projecting through the neck and pivotally connected at 12 to the upper end of an operating-lever 13, which is pivoted at 14 to a 55 bracket 15, secured to the cover. A flat spring 16, or, if preferred, a coil-spring, is secured upon the cover and forces the lower end of the lever 13, which is formed with a thumb or finger piece 17, upwardly to hold 60 the slide-valve in its closed position, as shown in Fig. 2.

It will be seen that by simply depressing the lower end or finger-piece 17 of the lever 13 the slide-valve 11 will be moved outwardly 65 to open communication between the ports 10 in the disks, and thereby permit the can to be filled or the contents of the same discharged. The parts may be readily taken apart for cleaning and repairs. The cover or 70 cap can be removed by unscrewing it from the can 1, and by removing the pivot 12 the slide-valve may be easily removed and cleaned. The can is particularly adapted for milking purposes, since the closure will keep 75 all dirt and foreign matter from the interior of the can, and should the same be kicked or overturned it will be impossible for the contents to be spilled.

From the foregoing description, taken in 80 connection with the accompanying drawings, the construction and operation of the invention will be readily understood without requiring a more extended explanation.

Various changes in the form, proportion, 85 and the minor details of construction may be resorted to without departing from the principle or sacrificing any of the advantages of this invention.

Having thus fully described my invention, 90 what I claim, and desire to secure by Letters Patent, is—

A valved closure for a can or receptacle, comprising a funnel, a connecting-neck, an attaching portion, apertured plates extending 95 across the neck, a slide-valve operating

between said plates and projecting beyond one side of the neck, a lever to operate said valve, pivoted on the attaching portion of the closure and detachably connected with 5 the slide-valve, and a spring bearing between the lever and the attaching portion of the closure, substantially as described.

In testimony whereof I have hereunto set my hand in presence of two subscribing witnesses.

WILLIAM JASPER SNOW.
